AIRPORT BUILDING

Samuel J. Solomon, 9101 Colesville Road, Silver Spring, Md. 20910, and John S. Samperton, Sumner, and William Procopiow, Bethesda, Md.; said Samperton and said Procopiow assignors to said Solomon

Filed Feb. 6, 1967, Ser. No. 5,711

Term of patent 14 years

(Cl. D13—1)

Fig. 1.

Fig. 2.

FIG. 1 is a top plan view of an airport building, showing our new design;

FIG. 2 is an enlarged side elevational view, looking in the direction of the arrows 2—2 in FIG. 1; and

FIG. 3 is an enlarged side elevational view, looking in the direction of the arrows 3—3 in FIG. 1.

We claim:

The ornamental design for an airport building, as shown.
